Application December 10, 1949, Serial No. 6,546

Term of patent 14 years

(Cl. D48—23)

To all whom it may concern:

Be it known that I, Albert V. Jernigan, a citizen of the United States of America, residing at Dallas, in the county of Dallas and State of Texas, have invented a new, original, and ornamental Design for Lighting Fixture, of which the following is a specification, reference being had to the accompanying drawing, forming part thereof.

In the drawing

Fig. I is a perspective view of a lighting fixture showing my new design;

Fig. II is a top plan view of the lighting fixture; and

Fig. III is side elevational view of the lighting fixture taken from the back side of Fig. I.

I claim:

The ornamental design for a lighting fixture, as shown.

ALBERT V. JERNIGAN.
